Primary Examiner — Susan E Krakower*Assistant Examiner* — Jerry Shiuan-Hua Hsu(74) *Attorney, Agent, or Firm* — Bradley J. Thorson; DeWitt LLP(57) **CLAIM**

The ornamental design for decorative fitting for vehicles, as shown and described.

DESCRIPTION

FIG. 1 is a perspective view of a decorative fitting for vehicles, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view thereof, shown in condition of use, mounted on a vehicle.

The broken lines illustrate environmental structure which forms no part of the claimed design.
